DISPENSING PACKAGE

Robert H. Van Sant, Alexandria, Va.

Application July 26, 1946, Serial No. 686,597

1 Claim. (Cl. 206—65)

1

This invention relates to holders and more particularly to those of a protective nature, the invention having for its object to provide a construction which is simple in parts, easy of manufacture, and less costly than those heretofore proposed.

With these and other objects in view the invention resides in the novel details of construction and combinations of parts as will be disclosed more fully hereinafter and particularly covered by the claim.

Referring to the accompanying drawings forming a part of this specification and in which like numerals designate like parts in all the views,

Fig. 1 is a side elevational view of a holder made in accordance with this invention;

Fig. 2 is a partial side elevational view of a modification of the holder illustrated in Fig. 1;

Fig. 3 is a top plan view of a holder similar to that illustrated in Fig. 2 but made in two halves provided with a hinge joint and a locking means for securing the two halves together; and

Figs. 4 to 10 inclusive are top plan views of various modifications of a single-cell type of holder.

There are many items on the market, and contemplated, which for one reason or another can be handled better if they are provided with a holder, and only by way of example and not of limitation such items as capsules and/or ampules are mentioned particularly if and when they are made of frangible, gelatinous and/or plastic material. This invention contemplates a holder for either one or a plurality of capsule-like items, and the holder may be fashioned in the latter case to correspond with the particular geometrical arrangement of the capsules in the group; that is to say, and as particularly illustrated in Fig. 3, the arrangement of the plurality of capsules may be in a straight line, but the capsules may be in other geometrical groupings or arrangements as found desirable. Generally speaking, the holder will be so fashioned that there will be a cell-like cavity therein for each of the capsules of the group.

Whereas most capsules are of circular transverse section, the cell of the holder of this invention may have various cross-sectional shapes as attempted to illustrate in the showings of Figs. 4 to 10. In the case of a capsule having, on its exterior surface, indentations or outstanding ribs or other conformations departing from the typical continuous circular surface, the holder may have a cell configuration as particularly il-

2

lustrated in Figs. 6, 7, and 8 to conform with such indentations, outstanding ribs or other departure from said typical continuous circular shape.

In any event, the internal shape and dimension of the cell of the holder will be such as to provide either entire or partial frictional engagement with the exterior surface of the contained capsule, so that said capsule will be gripped sufficiently by the holder to make unnecessary the provision of capsule-securing means, though if desired this invention contemplates also the provision of an adhesive medium interposed between the outer surface of the capsule and the inner surface of the cell of the holder, and/or it additionally contemplates the treatment of the substance of the capsule with liquid or heat in order to cause adhesion of these surfaces without the necessity of an added adhesive medium.

With particular reference to Fig. 1, a holder generally identified by the numeral 2 is provided for a plurality or group of similar hermetically sealed liquid-containing capsules identified by the numeral 3, said capsules arranged in abutting relation with each other as indicated at 4, each capsule being generally cylindrical and rounded at one end as shown at 5 but having its opposite end drawn or reduced in diameter in order to provide a teat having a short tip portion 6 which may be readily severed, cut or otherwise sundered as at the area 7 to open the capsule and thus permit the escape of its liquid content as when the sundered area of the tip portion is moved over a body surface (skin) in contact therewith.

The holder in this figure of illustration is made in one piece with a plurality of cells, one for each capsule, an edge view of said holder being similar to that illustrated in Fig. 3 except that the holder of Fig. 3 is made in two halves. In the modification shown in Fig. 1, the capsules are inserted endwise into the holder 2 to be retained therein in the general relative positions illustrated.

Preferably, though not of necessity, the walls of each cell of the holder 2 are slightly tapered, inwardly directed or reduced at one end, as indicated at 10, to conform with and serve as a stop for the rounded end portion 5 of the inserted capsule, or internal lugs or projections may be formed on the inner surface of the cell so that said capsule can be pushed into said cell a distance which is limited as when the rounded end of the capsule seats in the constricted or tapered portion of the holder. This restricted wall portion of the holder cell may be truncated as indicated in Fig. 1 to

provide an opening permitting the extreme rounded end of the inserted capsule to protrude therethrough and thus be exposed, or this portion of the holder cell may be so formed that said rounded end will not protrude beyond the end of the cell thereby making possible a flat holder extremity that will serve as a base upon which the entire assemblage may be stood, particularly in order that a medicament of light viscosity may not escape (leak) and be lost from the capsule after unsealing, as might occur when the assemblage was laid upon its side.

It is preferred, however, to have the truncated formation which provides an open end to the cell, for escape of air when the capsule is pressed into its cell because, as heretofore stated, the outer surface of each capsule may be in entire contact with the inner surface of its cell in order that the capsule may be retained by complete circumferential friction in the holder, and if the cell was closed at its end there would be an entrapment of air therein which would prevent the full insertion of the capsule and result in a possible misalignment of the teat ends of the capsules in the group.

It is also preferred that the holder have a corrugated or undulating outer surface so that the holder may be gripped better by the fingers, and to this end the undulations of said surface are formed substantially coaxial with the cylindrical inner surfaces of the cells of the holder. The extent of the holder longitudinally of the capsules may be made as desired, though it need be only sufficient to establish positive retention of the capsules in the holder and to provide sufficient area for grasping by the fingers.

In the modification illustrated in Fig. 2 the extent of the holder 20 is made greater than that of the holder 2, but it is otherwise similarly formed, and comprises a corresponding truncated or otherwise reduced end cell portion 21 which, however, is formed to seat the teat end of the inserted capsule instead of the completely rounded end 5. In other words, with this holder 20 the capsules are inserted in a reverse manner to that indicated in Fig. 1, and the greater extent of this holder will of course result in more protection to the contained capsule.

Referring to Fig. 3, the holder generally identified by the numeral 30 is made in two halves as indicated at 31 and 32, said halves joined at one end by a hinge 33 and provided at their other ends with any suitable clamping or locking means as indicated at 34 whereby the two halves are secured together. This holder is otherwise formed similarly to the holders illustrated in Figs. 1 and 2.

Figs. 4 to 10 inclusive illustrate end elevations of unitary cells of holders for single capsules having various cross-sectional shapes, though it will be understood that a holder for a plurality or group of capsules (as illustrated in Figs. 1, 2 and 3) can be modified in accordance with the teachings of Figs. 4 to 10. According to Fig. 4 the holder is adapted to contain a capsule of triangular cross-sectional shape; according to Fig. 9 the holder will conform to a capsule of rectangular shape either square or otherwise; according to Fig. 10 the holder is for a capsule of other polygonal shape (such as a hexagon); and according to Figs. 5 to 8 the holder is generally of circular cross-section to receive and retain a correspondingly shaped capsule. In Fig. 6 the circular holder has its wall provided with one or more inwardly directed portions (of longitudinal

extent or otherwise) such as 40 to conform with indentations formed on the outer surface of its contained capsule; in Fig. 7 the circular holder has its wall provided with one or more outwardly directed portions (of longitudinal extent or otherwise) such as 50 to conform with ribs or projections on the outer surface of its contained capsule; and the intent of Fig. 8 is to illustrate a generally circular holder having departures in wall construction from those formations heretofore described, such departures comprising an interior flattened area 60 and/or an outwardly directed flattened area 70, likewise conforming with similar surface construction of the contained capsule. The specific constructions of all of these figures, with the exception of that shown in Fig. 5, will prevent any rotation of a contained capsule about its longitudinal axis while in the holder.

The intent of this invention is to provide a holder the inner surface of the cell wall of which will, through entire or partial perimetric or circumferential contact, frictionally retain a capsule regardless of the specific outer surface configuration of the capsule. For example, it is conceivable that a capsule having inwardly extending surface indentations would fit and be retained in the completely circular cell of the holder indicated in Fig. 5; and a capsule having outwardly extending surface areas would also be retained in the holder of Fig. 5 if said capsule were made slightly smaller than the internal diameter of said holder, there being provided sufficient partial-circumferential frictional engagement of the contacting surface areas to result in the securement of the capsule in the holder.

Additionally, it is conceivable that the cell of a holder may contain two or more capsules of complementary cross-sectional shapes, each capsule cofitting with another due to the said complementary formation. For example, a circular cell may contain two semi-circularly shaped capsules, a rectangular cell may contain two triangularly shaped capsules or two or more smaller rectangular capsules, a polygonal cell may contain a plurality of triangularly shaped capsules or a combination of rectangular and triangular capsules, etc., or a combination of variously formed capsules may be fitted within a cell when they have external surfaces which are wholly or in part complementary with respect to each other. In other words, it is only required that the outer surface of a capsule engage the inner surface of the holder cell at areas providing sufficient surface friction therebetween to result in the retention of the capsule or capsules in the holder, regardless of the otherwise specific surface conformations thereof.

Therefore, in its broadest aspect, this invention is directed to the provision of a holder which will retain capsules of regular, or various eccentric, shapes as well as a capsule of a shape which completely conforms perimetrically to the shape of the holder. Additionally, it is conceivable that the holder may be so formed as itself to contain the liquid, to the exclusion of the provision of a capsule or ampule, whereby the reduced end of the holder cell may be cut, severed or otherwise sundered in order to permit escape of its contained liquid.

The holder may be formed of various materials such as metals, plastics, gelatines, relatively stiff fabrics, reticulate materials such as screening or other skeleton-like formations, glass, ceramics, etc., said holder being molded, stamped, rolled, or otherwise formed, either cold or under the in-

fluence of heat and pressure, and may be given coloration, ornamentation and/or other aesthetic appearance. In addition, the use of an adhesive tape, either singly or in combination with one of these holders, is contemplated as a means of securing a capsule in the cell of a holder, or in securing a plurality of capsules together as a group, it being considered unnecessary to particularly illustrate this means of securement. If desired, suitable adhesive media may be employed to provide greater adhesion between a capsule and its cell, such media comprising the application of glues, cements, welds, etc., as well as the employment of methods, ways and means resulting in cohesion and/or adhesion brought about through application of partial solvents, heat, pressure, etc.

According to this invention, a capsule is placed in a cell of the holder, the tip portion of the capsule is then severed or otherwise sundered to unseal the capsule, and then the holder is manipulated so that the sundered area of the capsule is moved over a body surface (skin) in contact therewith, whereupon the liquid content of the capsule by virtue of capillary action, and/or attraction is caused to flow from the capsule onto the body surface, the said sundered area of the capsule concurrently rendering a massaging effect. If the liquid in the capsule has a relatively high viscosity, an easier flow thereof may be attained by creating an air vent as by puncturing the opposite or rounded end of the capsule.

When the capsule or ampule is made of a material (such as glass or metal) which will create a harsh or sharp edge to the sundered area, such as to cut or otherwise harm the body surface when moved in contact therewith, the sundered capsule may forcefully be slipped bodily in the holder such as illustrated in Fig. 2 to bring the sundered body-contacting area substantially into the plane of the outer end of the restricted end portion of the holder cell, whereby the sharpness of said area will be guarded by said outer end of the holder and cause no damage to the body surface.

It is obvious that those skilled in the art may vary the details of construction and arrangements of parts without departing from the spirit

of this invention and therefore it is desired not to be limited to the exact foregoing disclosure except as may be required by the claim.

What is claimed is:

- 5 A package comprising a plurality of similarly formed capsules containing medicants, and a single holder for said capsules, each capsule having a reduced end simulating a teat provided with a frangible end portion, each capsule further
 10 having a longitudinal axis and a substantially rigid exterior surface the elements of which are arranged in substantial symmetry with respect to such axis, said holder comprising a unitary member having two opposed relatively fixed wall portions, said wall portions having oppositely facing complementally formed inner surfaces providing together a series of pockets within which said capsules are disposed in frictional engagement with said surfaces and in substantially tangential relation with each other, the depth of each pocket being less than the longitudinal length of its contained capsule, whereby the frangible end portions of said capsules project from their pockets at all times and may be
 15 readily broken without removal of the capsules from said pockets, the breaking of said end portions of said capsules permitting release of the medicants contained in said capsules.
